UNITED STATES PATENT OFFICE.

JOSEPH E. ROBIN, OF NEW YORK, N. Y.

COORDINATING SIGNALING SYSTEM.

Application filed April 21, 1921. Serial No. 463,324.

This invention relates generally to an electrical signaling system, and particularly to a system designated to transmit coordinated signals of dissimilar import to a plurality of receiving stations from a transmitting station.

The invention is useful for employment in any situation wherein it is desirable to coordinate activities at a plurality of distant

points by transmitting selectively different signals to several receiving stations, the several signals transmitted to each station forming a progressive series designated to regulate the activity at the receiving station, and the several series sent to all of the stations being coordinated so that the activities at all of the stations may be held to a uniform time schedule. An example of such use is the regulation of a theatrical performance, such as a vaudeville program. In such a situation it is desirable, in order to secure proper continuity of the performance, and prevent confusion, to inform the several performers or actors when they are to be ready, when to go on, etc., and to coordinate the activities of other participants such as the orchestra leader, and the electricians in charge of the stage lighting, spot light, etc. By furnishing the necessary or desirable warning signals, call signals, etc., and controlling them from a central transmitting station, the performance may be properly coordinated in itself, and held to a desired time schedule. Another illustrative use is the employment of the system in the presentation of moving pictures wherein it is desired to coordinate the work of the operator of the projecting apparatus and that of the orchestra with ancillary lighting or stage effects, or to synchronize an orchestral or musical number with changing scenic or lighting effects.

The general object of the present invention is to provide a signaling system which is simple, certain, and accurate in operation, and under control at a central transmitting station, and by which coordinated series of signals of different import may be transmitted to a plurality of distant receiving stations in a desired order or sequence.

Another object of the invention is the provision of such a system wherein the relationship of signals transmitted to different stations may be predetermined and varied selectively so that different signals of the series may be transmitted to the several sta-

tions simultaneously and in a selected order.

Another object of the invention is the provision of a signaling system in which a series of signals for each of the several receiving stations may be predetermined, and the several series of signals coordinated in time relationship so that different signals may be sent to the several stations simultaneously.

A further object of the invention is the provision of a signaling system including a central transmitting station and a plurality of receiving stations, wherein different signals arranged in coordinate series for the several receiving stations may be predetermined at the transmitting station, and constituent signals of the several series transmitted to the several receiving stations simultaneously.

Another object of the invention is the provision of a signal system including a plurality of receiving stations and a central controlling transmitting station from which the signals may be transmitted to the receiving stations either conjointly or independently of one another.

Another object of the invention is the provision of a signaling apparatus including a plurality of galvanometers disposed at the receiving stations and connected with a source of electrical energy through variable resistances disposed at a central control station, the resistances associated with the several galvanometer being operable in common by a control mechanism, so that the several resistances may be varied to vary the energization of the galvanometers simultaneously, the control mechanism being adjustable with respect to the several resistances, so that a given operation of the control mechanism may effect different changes in the several resistances.

Other objects of the invention will be pointed out hereinafter or indicated in the appended claims, or will be obvious upon an understanding of the apparatus described.

In general, the invention contemplates a plurality of variably operable indicating devices suitable for disposal at separate receiving stations, such as in stage dressing rooms, light controlling switchboards, musical director's stand, projecting machine operator's booth, and the like, which indicating devices may be equipped with suitable legends indicative of various information. One instrument fulfilling this requirement is

a suitable form of galvanometer having a dial bearing legends in association with an electrically operated pointer. These several indicating instruments are operably connected with a transmitting mechanism disposed in a central station. This transmitting mechanism includes independently operable signal-determining means associated with the several indicating devices and effective thereon independently, and arranged so that said signal-determining means may be set to predetermine signals or series of signals to be transmitted through the indicating devices severally. Signal-determining means fulfilling these requirements comprises a plurality of rheostats, one electrically connected with each of the indicating devices so that it is effective to vary the energization thereof to predetermined extents. The connection arms or switch levers of the several rheostats are independently adjustable so that they may be set at different points. Associated in common with the signal-determining devices is an operating mechanism operable to vary the effectiveness of all of the signal-determining devices upon the indicating devices concomitantly. A mechanical device fulfilling this requirement is a mechanical connection operable to move all of the contact arms of the rheostats so as to vary the resistances effective in the several galvanometer circuits. The various devices are suitably associated with a source of energy, such as an electric battery adapted to energize the galvanometers through their associated rheostats. Independently variable resistances may be disposed in the several galvanometers' circuits as balancing elements, whereby the impedance in the several circuits may be adjusted so that the indicating devices will calibrate with their controlling signal-determining devices.

A more specific understanding of the invention may be had by reference to the accompanying drawing which is supplied as an illustration of forms in which the invention may be embodied. It is to be understood, of course, that the illustrated forms are not intended as exhaustive of all the variations, adaptations, or forms in which the invention may be incorporated by exercise of the mechanical skill of the art.

In the said drawing Figure 1 represents diagrammatically an electrical system embodying my invention, and Figure 2 an alternative arrangement.

Referring now to Figure 1 of the drawing by means of the reference characters applied, let it be understood that the characters A, A', A², A³, designate respectively separate indicating devices adapted for disposal at different receiving stations. In the embodiment illustrated, these are shown diagrammatically as indicating galvanometers. Indicating device A is connected in an electrical

circuit by the wires 1 and 2 leading to a main circuit through the central or control station, galvanometer A' is similarly connected by the wires 3 and 4, galvanometer A² by the wires 5 and 6 and galvanometer A³ by the wires 7 and 8. The dials of these galvanometers are furnished with suitable indicating legends, appropriate to use of the system, which legends are here illustrated by the terms Call, Ready, Go, Stop, and Off, and the pointer of the galvanometer is adapted for association with these legends in accordance with the quantity of energization of the instrument. The indicating devices are connected severally with respective signal-determining devices, here diagrammatically illustrated as the rheostats a, a¹, a², a³. Each rheostat has suitable contact points for co-operation with its contact arm 10 to determine the amount of resistance effective in the circuit. The dial of each indicating instrument is calibrated with its associated rheostat with reference to the intended quantity of the current so that the variation of resistance in the circuit by movement of the contact arm 10 from point to point will cause the responsive movement of the pointer of the indicating device to bring it into indicating association with the intended legend. The several galvanometers are energized from a suitable source 11 through a main circuit 12 and 13, and the effective quantity of the main current may be established with reference to the potential of the source 11 by means of a suitable variable resistance 14. Likewise the normal quantity of the several galvanometer circuits may be established or balanced by the adjustment of suitable variable resistances 15, 16, 17 and 18, inserted therein.

As stated, the signal-determining devices A, A', A², A³, are grouped at the central control station. Conveniently associated with them for the information of the operator, indicating galvanometers b, b¹, b², b³, may be connected in the respective galvanometer circuits. These are supplied with indicating dials conforming to those of their associated instruments and calibrated therewith and with their respective signal-determining devices.

Operably associated with the signal-determining devices in common is an operating or master control mechanism, diagrammatically illustrated by the manually rotatable shaft 19 carrying the worms 20', 21, 22 and 23 operably engaging gears 24, 25, 26 and 27 respectively, which gears are fixed on the rotatable shafts of the contact arms 10. Said contact arms 10 are independently adjustable on their respective shafts so that they may be set at different degrees with respect to the said gears, the adjustable connections being illustrated by the set screws 10^a. The arrangement is such that opera-

tion of the shaft 19 will move the contact arms progressively from contact point to contact point, and thus vary the resistance in the several galvanometer circuits concomitantly. This, of course, will be effective to vary the positions of the pointers of the indicating instruments relative to their dials.

In conjunction with the indicating instruments at the receiving stations suitable visual or audible signals, designated by the characters D, D¹, D², D³, may be installed for calling attention to the indicating instruments, said signals being operable from the central station in any suitable fashion, as by a push button illustrated schematically and designed by "sig." in Fig. 1.

As illustrative of the use and operation of this system, let it be assumed that the several instruments A, A¹, A², A³, are in separate stage dressing rooms which are in use severally by different performers, and that according to the intended program the performer occupying the dressing room in which instrument A³ is installed is to appear first, followed in order by the performers occupying the dressing rooms in which are indicating instruments A², A¹, and A. Let it be assumed that the several signals designed to regulate the activity of the several performers, or indicating to them the progress of the program, may be designated by the dial legends Call, Ready, Go, Stop, Off. The operator at the control station predetermines the time relationship in which the several signals shall be transmitted to the different indicating instruments by setting the contact arms of the signal-determining devices in the proper relationship. In the supposed instance the contact arm of the rheostat a³ would be set so that it would make connection with the contact point of the resistance element requisite to cause the indicating instrument A³ to indicate Call before the contact arms of the other rheostats would be in position for cooperation with contact points in their instruments, and the contact arms of the rheostats a², a¹, and a would be set so that, upon operation of the control mechanism 19, they would be moved into cooperation with their contact points in the intended order; i. e., the contact arms of rheostat a² would be on Call when the contact arm of rheostat a³ were on Ready, contact arm a¹ would be on Call when contact arm of rheostat a² were on Ready, and connection arm of rheostat a on Call when connection arm a¹ were on Ready. The order in which the signals will be transmitted to the receiving instruments being thus predetermined, and all the connection arms being operated in common by the operating mechanism, it will be obvious that the transmission of the signals to the various stations will be positively co-

ordinated, so that the transmitting operator exercises certain control over the timing of the entire program. It is to be observed, however, that the priority of the several indicating instruments with respect to the series of signals may be established as desired, so that, instead of the order indicated by the illustrated arrangement, in which indicating instrument A³ stands first on the schedule, any one of the other instruments may be placed first on the schedule and the others following in any desired order. Moreover, the operator may transmit a desired signal to any one of the transmitting stations independently of the other stations by operating individually the contact arm of its control rheostat, and the dials of the indicating instruments may be provided with extraneous or additional indicating legends, and the rheostats with contact points coordinated therewith.

In Figure 2 is illustrated a modified or alternative arrangement which will serve to illustrate forms in which the system may be applied to situations requiring the transmission of special intelligence to the respective stations, such, for instance, as to the orchestra leader, the projecting booth, the stage director, and the switchboard electrician in a moving picture theatre. Here each indicating instrument is shown equipped with legends applying specifically to the activities controlled at its particular station. In the arrangement shown is employed the same relative associations of indicating instruments, control rheostats, and energizing circuits as have been described, but with another form of operative control mechanism. In this arrangement the energization of each rheostat and its associated indicating instrument is controlled by a switch 19^a arranged for electrical cooperation with its contact points 19^c. These switches are operatively associated with a common controlling device represented by the shiftable bar 19^b which may be actuated from the hand lever 19^d to open or close all of the switches simultaneously. The operative connection between the switches 19^a and the member 19^b is such that any switch may be disconnected from bar 19^b and operated individually and independently of the others, and the several rheostat arms 16 are individually adjustable. To facilitate disconnection of switches 19^a from rod 19^b, the pivotal connections between the rod and the switches may be of a readily severable type such as a reasonably close fitting cylindrical pin held in place by friction. This system may be employed in conjunction with a program for the guidance of the operator, in which, under each program number is set out the orchestra selection, the picture, the dramatic production, the stage setting, and the stage lighting, required for such number. Under the

guidance of this program, the operator will set the contact arms 10 of the several instruments at the proper contact points to secure the transmission of the desired signals to the respective stations, and then, at the proper time, will operate the control mechanism to close the switches 19^a, which will effect the transmission of the respective signals to the several stations. After the 10 start of the program number to which said signals pertain, the operator may operate the control mechanism to open the switches, and then may operate the switches 19^a individually from time to time if necessary, 15 to control any particular activity at any station during the presentation of the number as hereinafter described. Before the time for the next number to be produced, the operator will set the several contact arms 20 10 on the proper points, in conformity with his program, and, at the proper time, transmit all the said prearranged signals simultaneously by operation of the mechanism 19^b. In this fashion the progress of the 25 performance may be positively controlled and coordinated and, in the event of any sudden change in the order of the numbers on the program, all of the participants in the production, who may be located at relatively distant and inaccessible points, may be placed in possession immediately of the necessary information to preserve the desired continuity of the program. In conjunction with this arrangement may be employed, of course, the alarm signals D, D', 30 D², and D³ controlled from the operating board, as by means of the switches or push buttons 20.

Having thus described my invention, what 40 I claim is:

1. A signaling system for conveying information to persons at a plurality of stations to enable them to coordinate their activities, comprising a plurality of electrical- 45 ly operated indicating devices one of which is located at each station, each indicating device being adapted to give a plurality of indications which per se are of different character; a plurality of signal-determining devices one corresponding to each indicating device, said signal-determining devices being individually adjustable to provide for the 50 production simultaneously of different indications at the different stations; circuit connections operatively connecting each signal-

determining device with its respective indicating device whereby upon energization of the circuits each indicating device gives an indication in accordance with the setting of its signal-determining device; and means to simultaneously energize all of said circuits to produce indications at all of the stations simultaneously.

2. A signaling system for conveying information to persons at a plurality of stations to enable them to coordinate their activities, comprising a plurality of indicating devices, one of which is located at each station, each indicating device being adapted to give a plurality of indications which per se are of different character; a plurality of signal-determining devices one corresponding to each indicating device, said signal-determining devices being individually adjustable to provide for the production simultaneously of different indications at the different stations; means operatively connecting each signal-determining device with its respective indicating device; and control means operable to cause the display, simultaneously at the various stations, of indications in accordance with the setting of the various signal-determining devices.

3. A signaling system for conveying information to persons at a plurality of stations to enable them to coordinate their activities, comprising a plurality of indicating galvanometers one of which is located at each station, each galvanometer having a plurality of legends and a pointer associated therewith; a plurality of rheostats one corresponding to each galvanometer, said rheostats being individually adjustable to provide for the production simultaneously of different indications at the different stations; circuit connections operatively connecting each rheostat with its respective galvanometer, whereby upon energization of the circuits each galvanometer gives an indication in accordance with the setting of its rheostat; a variable resistance in each galvanometer circuit to provide an adjustment whereby all of the galvanometer circuits may be adjusted for energization by the same value of voltage; a source of current connected to energize all of the galvanometer circuits; and switching means operative to simultaneously control the flow of current in all of the galvanometer circuits.

JOSEPH E. ROBIN.
